BLOW-OFF APPARATUS FOR BOILERS

Filed Aug. 11, 1926

INVENTOR,

Russell R. Waterman
BY A.B. Bowman
ATTORNEY

UNITED STATES PATENT OFFICE

RUSSELL R. WATERMAN, OF LONG BEACH, CALIFORNIA, ASSIGNOR TO FARMERS' NATIONAL BANK OF GREENVILLE, OHIO, OF GREENVILLE, OHIO, A CORPORATION OF OHIO, TRUSTEE

BLOW-OFF APPARATUS FOR BOILERS

Application filed August 11, 1926. Serial No. 128,618.

My invention relates to blow-off apparatus for boilers.

The principal objects of my invention are; first, to provide a blow-off apparatus so constructed that it will draw or eject all the water from the boiler pumps and boiler pump lines; second, to provide a blow-off apparatus of this class which is novel in its construction, and, third, to provide a blow-off apparatus 10 of this class which is very simple and economical of construction, easy to install, efficient in its action, and which will not readily deteriorate or get out of order.

With these and other objects in view, as 15 will appear hereinafter, my invention consists of certain novel features of construction, combination and arrangement of parts and portions as will be hereinafter described in detail and particularly set forth in the appended claims, reference being had to the 20 accompanying drawings and to the characters of reference thereon which form a part of this application in which:

The figure in the drawing is an elevational 25 view of my blow-off and ejection apparatus showing the same diagrammatically and showing by legends the various elements to which my apparatus is adapted to be connected, some of the parts and portions broken 30 away and in section to facilitate the illustration.

The blow-off valve 1, ejector nozzle 2, ejector casing 3, pipe 4, pipe 5, pipe 6 and valve 35 7 constitute the principal parts and portions of my blow-off and ejection apparatus for steam power plants.

The water pipe 4, which conventionally extends from the boiler pump to the preheater or economizer, is ended before it reaches the 40 preheater and the casing 3 is fitted upon its end, the one cross arm or boss 3a of the casing 3 receiving the end of the pipe 5 which is connected to the preheater at the conventional 45 connection point for pipe 4. The pipe 5 extends into the casing 3 and is tapered so as to form the ejector nozzle 2 which ends close to the opposite side of the casing 3, the jet from the nozzle entering a short length of pipe 6 50 which is secured in the other cross arm or boss

3b of the casing 3. The blow-off valve 1 is fitted upon the pipe 6.

If a hand water pump is connected to the water pipe 4, a valve 7 is fitted upon the hand water pump line, this valve being closed 55 when the boiler supply pump is used.

When it is desired to pump water to the preheater in the conventional manner, the valve 1 is closed and water from the pump line 4 then enters the casing 3 from which it 60 passes by means of the nozzle 2 and the pipe 5 into the preheater in the direction of the arrows A. When the pump and pump lines require draining, the valve 1 is opened, the 65 blow-off pressure from the boiler through the preheater passes from the preheater through the pipe 5 and the nozzle 2 into the casing 3. Because the pipe 6 is placed opposite the nozzle 2, the jet or pressure from the nozzle 2 enters the pipe 6 passing through 70 the valve 1 in the direction of the arrow B. This causes a suction in the pump and pump line 4 in the direction of the arrow C.

Though I have shown and described a particular construction, combination and arrangement of parts and portions, I do not wish to be limited to this particular construction, combination and arrangement, but desire to include in the scope of my invention 75 the construction, combination and arrangement substantially as set forth in the appended claims.

Having thus described my invention, what I claim as new and desire to secure by Letters Patent is:

1. In a blow-off apparatus for boilers, the combination of a preheater supply pipe provided with an ejector nozzle at the remote end from the boiler, said nozzle having a restricted end directed away from the boiler, a casing enclosing said nozzle, a boiler pump pipe communicating with said casing at the side of the nozzle, and a discharge water pipe communicating with said casing in alignment with said nozzle and toward which said nozzle is directed, said discharge water pipe being provided with a blow-off valve.

2. In a blow-off apparatus for boilers, the combination of a preheater supply pipe, said pipe being provided with an ejector nozzle 100

on its extended end remote from the boiler, said nozzle having a restricted end directed away from the boiler, an outlet pipe in alignment therewith and toward which said nozzle is directed, a casing surrounding the adjacent ends of and supporting said nozzle and said discharge pipe and forming an ejector therewith, and a boiler feed pump pipe connecting with said casing at the side of the nozzle.

10 3. In a blow-off apparatus for boilers, the combination of a preheater supply pipe, said pipe being provided with an ejector nozzle on its extended end remote from the boiler, said nozzle having a restricted end directed away from the boiler, an outlet pipe in alignment therewith and toward which said nozzle is directed, a casing surrounding the adjacent ends of and supporting said nozzle and said discharge pipe and forming an ejector therewith, a boiler feed pump pipe connecting with said casing at the side of the nozzle, a hand pump pipe connected with said boiler feed pump pipe, and a valve in said hand pump pipe.

15 4. In a blow-off apparatus for boilers, the combination with a boiler preheater supply pipe, of an ejector in connection with the preheater supply pipe, a boiler pump pipe connected with the ejector, an outlet pipe in connection with the ejector, and a blow-off valve in said outlet pipe, the flow of water from the boiler pump pipe being normally from the latter to the preheater supply pipe 20 through the ejector when the blow-off valve is shut off, but from the boiler pump pipe to the outlet pipe when the valve is open.

25 5. In a blow-off apparatus, the combination with a boiler supply conductor and a boiler feed pump conductor, of an ejector nozzle on the boiler supply conductor, a casing enclosing the discharge end of the nozzle, said boiler feed pump conductor communicating with the casing at the side of the nozzle, and a discharge conductor connected to and extending from the casing in alignment with the nozzle, the nozzle on the boiler supply conductor being directed toward the discharge conductor.

30 50 In testimony whereof, I have hereunto set my hand at Los Angeles, California, this 20th day of July, 1926.

RUSSELL R. WATERMAN.
